UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

RAILWAY CAR

Application filed September 3, 1931. Serial No. 560,892.

The invention relates to railway freight cars and more particularly to so called "mill type gondolas," wherein the lower part of the end wall is hinged or pivoted to the car so that when in upright position it forms an end wall and the car may be used as an open top or gondola car. When it is desired to use such a car to haul long pipe, telegraph poles, girders or such ladings which are longer than the car, the end wall or end gate is lowered or swung to a horizontal position so that it lies on the floor of the car so that the lading may be positioned over it.

Such cars are used to haul steel plates, rails, beams and other similar material which is difficult to block in the car and which shifts longitudinally of the car, exerting a great horizontal thrust upon the end gate, therefore, the end gate must be very strong, and while the gates themselves are made very strong, it is also desirable to provide means adjacent the vertical and lower horizontal margins of the gate through which the horizontal thrust is transmitted to the car body preferably independent of the pivoting or hinging means.

When the gates are in upright position such cars are used to haul sand, cherts and other similar plastic material which, when the gate is slightly raised by coupling impact or rough track, creeps under the gate and raises it upwardly, causing it to be jammed in its fasteners and furthermore making it difficult to raise or lower the door. Furthermore, such impact raises the end gate causing undue stress upon the hinges and fasteners and also causing uneven stresses which bind the gate in its guides like a bureau drawer. One of the objects of the invention is to provide means to restrict the upward movement of such a pivotal end gate, which means also preferably restricts the backward movement (towards the car) when the gate is in upright position and which means also preferably restricts the backward movement of the gate when in lowered position. This last mentioned feature is desirable to resist the inertia movement of the door caused by the movement of the car in service and coupling impact.

A further object of the invention is to provide means for holding the associated parts of the pivoting means together.

This invention is an improvement upon the construction disclosed in my co-pending application 313,906, filed October 20, 1928, which shows and claims means for pivotally attaching an end gate to a railway car and also shows and claims the correlation between the gate and associated parts of the car.

In the drawings:

Fig. 1 shows partial elevation of a railway car equipped with my invention.

Fig. 2 is a plan view of Fig. 1.

Fig. 3 is a section along 3—3 of Fig. 1.

Fig. 4 is a side elevation of Fig. 1.

Fig. 5 is an enlarged section on 5—5 of Fig. 1.

Fig. 6 is a fragmentary end elevation showing the lower corner of the gate and its associated parts.

Fig. 7 is an enlarged section on 7—7 of Fig. 1 showing gate in upright position.

Fig. 8 is similar to Fig. 7 and shows the gate in lowered position.

In the drawings the usual parts of the car are shown, such as, the floor 2, center sills 3, side sills 4, side wall 5, including the top chord 6, striking casting 7, and end gate 8.

Each of the spaced apart side walls 5 have an inwardly projecting portion 10 against which the end gate 8 rests when in an upright position and the car is also provided with a projection or abutment 12 against which the lower part of the end gate 8 rests so that any horizontal thrusts against the end gate, due to shifting ladings, etc., is transmitted to the inwardly projecting portions 10 of the side walls and the projections 12. In the mill type gondola car the end gate is hinged or pivoted adjacent its lower portion so that it may be swung or dropped to rest on the floor and repose in a horizontal position.

In my construction the end gate is provided with oppositely projecting pintles 20 adjacent its lower margin which engage sockets or bearings 21 in the adjacent side walls 5 of the car which construction forms the pivot or hinge for the end gate 8.

The socket comprises a vertical slot (see 100

Fig. 7) open at the top so that the end gate may be lowered into it from above. A bolt 23 may be used to retain the pintles 20 in their respective sockets 21. The bottom of this vertical slot is preferably rectangular (see Fig. 7) to allow for a certain amount of accumulation of dirt, sand or chats, etc., without interfering with the hinge movement of the gate. Lateral clearance is provided between the 10 pintle 20 and the socket 21 to allow for irregularities of workmanship and also to assure easy operation of the gate even if it is bent or distorted.

The end gate 8 illustrated comprises a metallic plate formed with a plurality of substantially horizontal corrugations 30 which terminate (31) within the plate adjacent to the opposite margins thereof so as to provide a flat portion or abutment 32 to engage the 20 inwardly projecting portion 10 of the side walls.

The lower portion of the gate is also formed to abut against the projection 12 on the under frame. The top of the end gate is reinforced 25 by an angular chord 35 secured to the top flange, 36. The bottom of the end gate is reinforced by an angular member 40 secured to the bottom flange 41. The end gate is also provided with vertical flanges 43 at the side 30 margins thereof. One vertical flange 43 and the bottom flange 41 are secured together by a gusset 46 and the pintle 20 is preferably secured to this gusset. In the form illustrated the gusset 46 and the pintle 20 are an integral 35 casting.

The member or bracket 50 is secured to the underframe, floor, or any convenient part of the car and has a portion above a part of the gate so as to restrict the upward movement of the gate when it is in upright position. In the form illustrated the member 50 is provided with a horizontally projecting lip 51 which overlaps the vertical flange 52 of the angular member 40. The member 50 may extend continuously from side to side of car, 40 or may comprise a plurality of spaced apart members as shown in Figure 2.

I also preferably arrange this member 50 so that a portion (51) of it will be engaged by 50 the end gate 8 when in a lowered position (see Fig. 8) and prevent the gate from moving horizontally along the floor, due to its own inertia caused by the sudden starting or stopping of the car. The portion 51 overlaps the 55 flange 52 of the angular member 40 so as to restrict the upward movement of the door when in lowered position.

A portion 54 also is arranged to restrict the movement of the end gate longitudinally of 60 the car when in upright position (see Fig. 7). In other words the end gate fits between spaced apart parts of the car, for instance, the projection 10 or abutment 12 and the portion 54, to restrict the movement of the gate 65 in either direction longitudinally of the car.

The accompanying drawings illustrate the preferred form of the invention, though it is to be understood that the invention is not limited to the exact details of construction shown and described, as it is obvious that various 70 modifications thereof, within the scope of the claims, will occur to persons skilled in the art.

I claim:

1. In a railway car, the combination of a drop end gate pivotally attached to the car 75 adjacent its lower margin, and a member secured to the car body which is positioned above a part of said gate so as to restrict the upward movement of the gate when in upright position.

2. In a railway car, the combination of a drop end gate pivotally attached to the car adjacent its lower margin, a car part engageable with said gate when in upright position to restrict the forward movement of the gate, 85 and a member secured to the car body which is positioned above a part of said gate so as to restrict the upward movement of the gate when in upright position.

3. In a railway car, the combination of a drop end gate pivotally attached to the car adjacent its lower margin, a car part engageable with said gate when in upright position to restrict the forward movement of the gate, and a member secured to the car body which is positioned above a part of said gate so as to restrict the upward movement of the gate when in upright position, said member engageable with said gate when in upright position to restrict the backward movement of 100 the gate.

4. In a railway car, the combination of a drop end gate having a lower horizontal flange and pivotally attached to the car adjacent its lower margin, and a member secured to the car body which is positioned above said flange of the gate so as to restrict the upward movement of the gate when in upright position.

5. In a railway car, the combination of a drop end gate pivotally attached to the car adjacent its lower margin, and a member secured to the car body which is positioned above a part of said gate so as to restrict the upward movement of the gate when in upright position, said member engageable with said gate when in upright position to restrict the backward movement of the gate, said member also engageable with said gate when in a lowered position to restrict the backward movement of the gate.

6. In a railway car, an end gate pivotally attached to the car adjacent its lower margin which fits between spaced apart parts of the car so as to restrict movement of the gate in either direction longitudinally of the car in combination with an element which overlaps a portion of the gate so as to restrict the upward movement of the gate.

7. In a railway car, the combination of a 120

drop end gate pivotally attached to the car adjacent its lower margin, and a member secured to the car body which is positioned above a part of said gate so as to restrict

- 5 the upward movement of the gate when in upright position, said member engageable with said gate when in upright position to restrict the backward movement of the gate, said member also engageable with said gate
- 10 when in a lowered position to restrict the backward movement and upward movement of the gate.

8. In a railway car, the combination of spaced apart side walls, each provided with an open top vertical slot, a drop end gate provided with oppositely projecting pintles adjacent its lower margin which engage the slots in the adjacent side walls to form pivots for the end gate, said end gate having a horizontal portion adjacent its lower margin, and a member secured to the car body having a part positioned above said horizontal portion when the gate is in upright position to restrict the upward movement thereof.

9. In a railway car, the combination of spaced apart side walls, each provided with an open top vertical slot, a drop end gate provided with oppositely projecting pintles adjacent its lower margin which engage the slots in the adjacent side walls to form pivots for the end gate, said end gate comprising an angular member adjacent the lower margin thereof having a horizontal portion and a flange, and a member secured to the car body having a part positioned above said horizontal portion when the gate is in upright position to restrict the upward movement thereof, said part being positioned above said flange when the gate is in lowered position to restrict the upward movement thereof.

GARTH G. GILPIN.
